FIG. 1 is a front view showing a first image in a sequence of a display screen with transitional graphical user interface; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; and FIG. 7 is a front view of a seventh image thereof. The appearance of the graphical user interface sequentially transitions between the images shown in FIGS. 1-7. The process or period in which one image transitions to another image forms no part of the claimed design. The outermost solid-line rectangle illustrates the perimeter of a display screen. The broken lines outside this perimeter illustrate a user device. The broken lines within this perimeter illustrate features of a graphical user interface. The broken lines form no part of the claimed design.
